COMBINED COSMETIC AND TOTE BAG

Julia Raymond Rosenblum, 6 W. 77th St.,
New York, N.Y. 10024

Filed Apr. 16, 1970, Ser. No. 22,462

Term of patent 14 years

Int. Cl. D3—02

U.S. Cl. D87—3

FIG. 3.

FIG. 1.

FIG. 4.

FIG. 5.

FIG. 6.

FIG. 2.

FIG. 7.

FIG. 1 is a front elevational view of a combined cosmetic and tote bag showing my new design;

FIG. 2 is an exploded isometric view thereof;

FIG. 3 is an end elevational view thereof, looking at the left side of FIG. 1;

FIG. 4 is an end elevational view thereof, looking at the right side of FIG. 1;

FIG. 5 is a top plan view thereof with the carrying strap broken away for convenience of illustration;

FIG. 6 is a bottom plan view thereof; and

FIG. 7 is a rear elevational view thereof on a reduced scale, the carrying strap being broken away for convenience of illustration.

I claim:

The ornamental design for a combined cosmetic and tote bag, substantially as shown and described.
